(57) **CLAIM**

The ornamental design for a multiple purpose pole stand, as shown and described.

DESCRIPTION

FIG. 1 is a front elevational view of a multiple purpose pole stand showing my novel design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view of a multiple purpose pole stand of the present invention; and,

FIG. 8 is a perspective view of an alternate embodiment of a multiple purpose pole stand of the present invention.

The broken lines shown in FIGS. 7 and 8 are for illustrative purposes only and form no part of the overall claimed design.
